(57) **CLAIM**

We claim the ornamental design for a knob for a stand for measuring instruments, as shown and described.

DESCRIPTION

FIG. 1 is a front perspective view of a knob for a stand for measuring instruments showing our new design; FIG. 2 is a front view thereof, the rear view being identical thereto;

FIG. 3 is a left-side view thereof, the right-side view being identical thereto;

FIG. 4 is a top view thereof;

FIG. 5 is a bottom view thereof;

FIG. 6 is a cross-sectional view thereof, taken along line 6-6 shown in FIG. 4; and,

FIG. 7 is a perspective view thereof shown in use condition, the broken line showing of an extra knob for a stand for measuring instruments forming no part of the claimed design. The broken lines depict environmental subject matter only and form no part of the claimed design.
